(57) **CLAIM**

The ornamental design for packaging, as shown and described.

DESCRIPTION

FIG. 1 is a front perspective view of a packaging showing our new design.

FIG. 2 is a top plan view thereof.

FIG. 3 is a bottom plan view thereof.

FIG. 4 is a side elevational view thereof. An opposite side elevational view is identical thereto.

FIG. 5 is a top perspective view thereof in a partially opened state.

FIG. 6 is a top plan view thereof in the partially opened state.

FIG. 7 is a bottom plan view thereof in the partially opened state.

FIG. 8 is a side elevational view thereof in the partially opened state. An opposite side elevational view thereof in the partially opened state is identical.

FIG. 9 is a side elevational view thereof in a slightly opened state. An opposite side elevational view thereof in the slightly opened state is identical.

FIG. 10 is a top perspective view thereof in a fully opened state; and,

FIG. 11 is a top plan view thereof in an unfolded state as a plane sheet.
